(57) **CLAIM**

We claim the ornamental design for a two-stage engine charge air system with branch conduits, as shown and described.

DESCRIPTION

FIG. 1 is a perspective view of a two-stage engine charge air system with branch conduits;

FIG. 2 is a front elevational view of the system of FIG. 1; FIG. 3 is a rear elevational view of the system of FIG. 1; FIG. 4 is a right-side elevational view of the system of FIG. 1;

FIG. 5 is a left-side elevational view of the system of FIG. 1;

FIG. 6 is a top plan view of the system of FIG. 1; and, FIG. 7 is a bottom plan view of the system of FIG. 1. The broken lines shown in the views depict environmental subject matter only that forms no part of the claimed design.
